UNITED STATES PATENT OFFICE.

WILLIAM H. SNYDER, OF WAYNESBOROUGH, PENNSYLVANIA.

TRACTION-ENGINE.

SPECIFICATION forming part of Letters Patent No. 314,072, dated March 17, 1885.

Application filed December 20, 1884. (No model.)

To all whom it may concern:

Be it known that I, WILLIAM H. SNYDER, a citizen of the United States, residing at Waynesborough, in the county of Franklin and State of Pennsylvania, have invented certain new and useful Improvements in Self-Steering Attachments for Traction Plowing-Engines; and I do hereby declare the following to be a full, clear, and exact description of the invention, such as will enable others skilled in the art to which it appertains to make and use the same.

My improvement consists of an attachment which I term a "furrow-pilot," adapted to be applied to the swiveling truck of an ordinary traction-engine, when such engine is to be used for operating a gang of plows, the furrow-pilot being provided with a runner designed to run in the last furrow, whereby the traction-engine can be automatically steered by such furrow-pilot.

In order that my invention may be clearly understood, I have illustrated in the annexed drawings, and will proceed to describe, some practical forms thereof.

Figure 1 represents a side elevation of a traction plowing-engine with my invention attached thereto. Fig. 2 is a plan view of the same. Fig. 3 is an end elevation of the same. Figs. 4, 5, 6, 7, and 8 illustrate modifications of my invention.

The same letters of reference indicate identical parts in all the figures.

The furrow-pilot illustrated in the drawings consists of a frame, B, a laterally-projecting bar, B', on the forward beam of frame B, and a runner attached to bar B'.

The runner shown in Figs. 1, 2, and 3 consists of a wheel, C, having a V-shaped rim, 40 and journaled on a stud-axle, b, of bar B', which stud-axle stands at an angle of about forty-five degrees, so that the V-shaped rim of wheel C can run in the angle of the furrow, as best shown in Fig. 3. Instead of a single wheel, C, 45 a pair of such wheels hung on a yoke, C', as shown in Figs. 4 and 5, may be used, the yoke being suspended at its center from the stud-axle b. The advantage of using a pair of runners is that the furrow-pilot is not so apt to 50 be thrown out of the furrow by obstructions therein, because either one of the runners re-

mains in the bottom of the furrow while the other is riding over the obstruction.

The form of the runner and the manner of suspending it may be varied. Figs. 6 and 7 55 illustrate a runner consisting of a pivoted shoe, while Fig. 8 shows a runner consisting of a flat-rimmed wheel turning on a horizontal axis.

The frame of the furrow-pilot is pivoted to 60 clips d on the axle D of the swiveling truck of the traction-engine, and in the example illustrated projects forward from said axle so that the runner of the furrow-pilot runs in advance of swiveling truck. This position of 65 the furrow-pilot is not essential, however.

Provision is made for an adjustment of the furrow-pilot to govern the distance at which the traction-engine shall run along the furrow. The provision illustrated consists of the 70 adjustability of the bar B', which carries the runner, the bolts which secure the bar passing through slots in the frame B of the furrow-pilot, as shown in Fig. 2.

The swiveling truck of the traction-engine 75 is associated with a steering-gear, preferably such as shown, which is like that described in United States Patent No. 243,881. In using a traction-engine provided with a furrow-pilot substantially such as described for plowing purposes, the runner is caused to hug the side of the furrow, the steering-gear being so held that the swiveling truck of the engine has a slight tendency to run away from the furrow. The steering-gear may then be fastened, if desired, because the furrow-pilot will automatically steer the engine in exact conformity with the line of the last furrow. This particular mode of manipulating the steering-gear is not essential, because even if such 90 gear is not so held the furrow-pilot will steer the traction-engine with sufficient accuracy and certainty for all practical purposes.

The furrow-pilot is hinged to the axle of the swiveling truck, first, in order that it may 95 follow the furrow without being influenced by the motions of the truck in following the inequalities of the ground, and, secondly, in order that it may be turned up out of action.

The drawings illustrate a steam hoisting-gear for lifting the furrow-pilot, consisting of a hoisting rope or chain, E, which runs from the

forward end of the furrow-pilot over sheaves $e\ e'\ e''$ to the cross-head f of the piston-rod F' of a steam hoisting-cylinder, F , the latter being also used to operate the hoisting rope or 5 chain G , from which the gang of plows are to be suspended in the manner described in my application for a United States Patent filed October 18, 1884, Serial No. 145,873. In order that the furrow-pilot may be held elevated by 10 the rope or chain E irrespective of the piston-rod F' , a loop or ring, E' , is formed on it, so that it may be hooked to a hook, E'' . A separate steam hoisting-cylinder may be used for operating the hoisting rope or chain E only, as 15 indicated by dotted lines in Figs. 1 and 2.

The furrow-pilot may be applied to any known style of traction-engine which has a swiveling truck.

The details of construction and arrangement 20 may be greatly varied without departing from the spirit of my invention. At the same time I desire to state that I do not claim, broadly, a furrow-pilot adapted to aid in steering a traction-engine in plowing. The distinguishing 25 feature of my invention is a furrow-pilot adapted to be attached so as to act on the swiveling truck of a traction-engine.

I claim as my invention—

1. A furrow-pilot for traction plowing-engines adapted to be pivoted to the swiveling 30 truck thereof, substantially as and for the purpose set forth.

2. The combination, substantially as before set forth, of the swiveling truck of a traction plowing-engine and the furrow-pilot pivoted 35 thereto.

3. The combination, substantially as before set forth, of the swiveling truck of a traction plowing-engine and the laterally-adjustable furrow-pilot pivoted thereto. 40

4. The combination, substantially as before set forth, of the swiveling truck of a traction plowing-engine, the steering-gear, and the furrow-pilot pivoted to the said truck.

5. The combination, substantially as before set forth, of the swiveling truck of a traction-engine, the pilot pivoted thereto, and a hoisting rope or chain for lifting the pilot out of action. 45

In testimony whereof I affix my signature in 50 presence of two witnesses.

WILLIAM H. SNYDER.
